UNITED STATES PATENT OFFICE.

CHAUNCEY E. RICHARDSON, OF DULUTH, MINNESOTA.

DESIGN FOR A SPOON, &c.

SPECIFICATION forming part of Design No. 21,602, dated June 7, 1892.

Application filed May 2, 1892. Serial No. 431,571. Term of patent 3½ years.

To all whom it may concern:

Be it known that I, CHAUNCEY E. RICHARDSON, a citizen of the United States, residing at Duluth, in the county of St. Louis and State 5 of Minnesota, have invented and produced a new and original Design for Spoons and Similar Articles; and I do declare the following to be a full, clear, and exact description of the same, reference being had to the accompanying drawing, forming a part thereof.

This design is adapted especially for the city of Duluth, Minnesota, and is characteristic of that city and its recently-discovered rich deposits of ore, more particularly iron, 15 and for this reason it is contemplated to manufacture the spoon from iron or other metal mined in the immediate vicinity of Duluth.

In the accompanying drawings the figure is a plan view of a spoon exhibiting my design.

20 The leading feature of my design is the representation of a scepter terminating at its upper end in a crown, the two together forming the handle of the spoon. The handle may

be approximately cylindrical in cross-section, thereby giving more perfectly the exact representation of a scepter and crown, or it may be more or less flattened. The upper portion 25 of the scepter below the crown has a smooth outline on parallel lines and near its lower end is formed with a slight enlargement, and 30 its lower end has a diverging outline, as shown, and terminates in the bowl of the spoon, which bowl may be of any suitable shape. The spoon may be otherwise suitably 35 ornamented with words, scrolls, mottoes, and the like.

What I claim is—

The design for a spoon or similar articles, substantially as shown and described.

In testimony whereof I affix my signature in 40 presence of two witnesses.

CHAUNCEY E. RICHARDSON.
